UNITED STATES PATENT OFFICE.

CLARENCE D. TRUSSELL, OF POUGHKEEPSIE, NEW YORK.

TEMPORARY BINDER AND METHOD OF FORMING THE SAME.

1,194,684.

Specification of Letters Patent. Patented Aug. 15, 1916.

Application filed June 2, 1915. Serial No. 31,668.

To all whom it may concern:

Be it known that I, CLARENCE D. TRUSSELL, a citizen of the United States of America, residing in Poughkeepsie, in the county of Dutchess and State of New York, have invented certain new and useful Improvements in Temporary Binders and Methods of Forming the Same, of which the following is a specification:

10. My invention relates to temporary binders and to the method of forming the covers thereof.

My invention is illustrated in connection with that type of binder wherein half rings or prongs are mounted upon a spring prong carrying plate, and the said prongs having operative connections between their edges, are pressed by the plate either way from a central position whereby they are spring-20 held either in the open or the closed position to which they may be adjusted. Some of the parts of my invention, as hereinafter set forth, are useful in other connections.

The invention has for its object to provide an improved construction of cover adapted for use with such temporary binders, and which is also capable of use for other purposes, which is of simple construction, cheaply made and durable, and which 30 contains an improved hinge joint, by the use of which I am enabled to extend the material of which the cover is composed continuously through the extent thereof so that the same is of substantially uniform thickness throughout, and particularly at the back portion, and this hinge joint enables the covers to lie in the desired position either open or closed, and an object of the invention is also to provide a method whereby the 40 cover is formed.

Another object of the invention is that by the use of the improved cover, having its back portion of the full strength of the sides, I am enabled to provide a strong support for the metal parts.

A further object of the invention consists in the provision of simple and economical opening means for the prongs.

In the construction of temporary binders and other like books, it has been the custom to provide a cover with an outer lining of cloth or leather, which was usually mounted by means of some adhesive, such as glue or paste, upon a body or backing of board or

heavy paper. The application of this lining 55 produced a tendency to curl the boards outward at their edges, and to overcome this it has been the custom to line the said body with an inner lining of paper, cloth, etc., which restored the back to a substantially 60 flat condition. The practice has been, so far as I am aware, in covers of this character to omit part, for instance the body portion, in that portion of the cover constituting the back, thereby producing a back which is 65 thinner than the rest of the cover and accordingly sufficiently flexible to enable it to stay in position. The said cover, therefore, does not have its back formed of continuous layers throughout. In the construction of 70 such covers it has been the practice to paste or suitably secure the separated parts constituting the sides or body to the cloth or the outer lining. This lining cloth or leather, if leather be employed, is then 75 folded over the edges of the body portion, and the inner lining pasted on the inside so as to cover such folded over parts. This has all been hand work. A consequence of such 80 method is that the back, which has the function of supporting the book, is the weakest part of the cover, and correspondingly less able to perform this function. The production of such cover requires many hand operations and is slow and expensive.

My invention consists in the provision of a cover which is formed of a body portion having on the outer side the desired lining, and in forming the said several layers continuously through the entire extent of the 90 cover, and in then forming, at the place where it is desired that the back shall be, hinges on each side of the said back portion in the shape of grooves, which are located substantially parallel to each other and 95 are of sufficient width to enable the easy flexing of the covers.

My invention further consists in lining the inner part of the body portion of the cover with a coating of liquid applied thereto 100 which effectively overcomes the tendency of the cover to warp.

A further object of my invention is to improve the process of producing covers by treating a sheet of fibrous material by applying an outer liner thereto so as to cause the same to adhere. This sheet is cut into 105 cover blanks, each of which has hinges

formed therein. The inner surface of the sheet either before or after the same is cut into cover blanks, but preferably after, is treated as with a liquid to overcome the 5 warping tendency, whereby covers available for the reception of metal binder parts are produced.

A further object of my invention is that by the use of the improved and strengthened 10 back provided I am enabled to employ, with special advantage in the way of securing and holding the same, inner loose leaf binding mechanism and outer retaining devices, which are secured together by means which 15 pass through the said back portion.

A further object of my invention is in the provision of simple and economical opening means for the prongs.

A desirable form in which my invention 20 may be embodied is illustrated in the accompanying drawing, wherein—

Figure 1 is a perspective view of a temporary binder constructed according to my invention; Fig. 2 is a longitudinal section 25 of the book on the line 2—2, Fig. 1, partly broken, showing the book opened and the prongs drawn apart; Fig. 3 is a side view on an enlarged scale of the cover, the outer lining being at the bottom portion; Fig. 4 is a cross-section on the line 4—4 of Fig. 2, on an enlarged scale; Fig. 5 is a plan 30 view of the spring prong-carrying plate partly broken; Figs. 6 and 7 are elevation and end views respectively of the back 35 plate; Fig. 8 is an end view on an enlarged scale of the spring plate and the prongs.

According to my invention the temporary binder, or other similar device, is provided with a cover A, the construction of which 40 forms an important part of the invention. The body or backing B of this cover is formed of suitable material, for which purpose a good grade of paper of the kind known as cover paper, and which is some- 45 what flexible and of a fairly heavy weight, has been found well adapted. Paper board may be employed for this purpose, if desired, and the weight of the backing or the number of plies employed are variable as de- 50 sired. For the particular book illustrated I have found that a backing of one-ply of the kind of paper stated gives good re- 55 sults. Upon this backing is secured on the outside in the usual manner as by paste or glue, a lining C which may be of textile fab- 60 ric, such as cloth, or it may be of leather, or of any of the other substances usually em- 65 ployed for this purpose. I have illustrated this lining as being formed of cloth. As 70 heretofore stated, the application of the lining to the backing has a tendency to draw the backing so that it will no longer lie in the flat shape desired. To overcome this 75 tendency I apply to the inner side or sur- 80 face of the body portion or backing, as illus-

trated conventionally at D, a washing or coating of fluid, and this I have found effectively overcomes the tendency of the backing to warp in the direction of the liner. I have employed, heretofore, for this purpose, 70 a solution of book binders' paste in water, which constitutes an adhesive solution, and this I have found admirably accomplishes the purpose. I have also washed the said inner surface or backing with a solution of alum in water, and this, likewise, overcomes the tendency to warp. I believe that the desirable result accomplished is produced by a slight shrinking of the inner face, to which the said liquid is applied, but I am not positive as to this. I have ascertained, however, by actual use, that an adhesive solution or a 75 solution of adhesive material which forms a coating over the inside of the backing, is not necessary to overcome the warping 80 tendency, but that this may be accomplished by a solution or by a liquid which soaks into the fibers without forming a coating thereon. The liquid which I have employed for this purpose is spread evenly over the inner 85 surface of the backing B so as to cover the same, and when the said cover has dried the said liquid, whether the solution of book binders' paste be employed or any adhesive solution, will be found to have been absorbed into the body of the fiber backing 90 B so as to be practically indistinguishable from the surface. The body B, lining C and coating D extend continuously throughout the area of the cover, and the said cover 95 blank is substantially of a uniform and even thickness throughout.

According to my method the outer lining is applied to the body in a large sheet in the manner described, and when the sheet has 100 been properly dried it is cut up into blanks approximately the size of the cover desired, and the corners of the covers thereupon preferably rounded as indicated in the drawings, either during the said cutting or afterward. The hinge joints are then formed in the covers preferably in a hot press. The inner coating is preferably applied as the last step after the cover is pressed. The cutting of the blank out of the sheet may be 110 performed in the ordinary paper cutting machine, wherein a stack of sheets may be placed and which machine is usually provided with a clamp or press for firmly holding the material being cut, and in such case 115 the rounding of the corners, if desired, may be subsequently performed by a round knife, or the covers may be punched out of the sheet by male and female dies. It will be found that the edges of the cover so produced will be sharp and distinct; that they 120 will not fray in use but will maintain their shape, and that the said covers, although produced at a small fraction of the expense 125 of producing the ordinary cover having the 130

edge of the lining turned over and pasted to the inside, will be equal in appearance thereto and that the finish of the edge will be substantially as good.

5 An important feature of my invention is the provision of a hinge joint, by means of which the cover may be folded, and which will permit the cover to remain in either an open or closed position, as desired. Such hinge joint is provided by forming two grooves E, E¹ in the material of which the cover is composed. These grooves are pressed inwardly from the lining C and extend through the entire layers or plies forming the cover, as shown in Fig. 3. They are parallel and in such position that the portion F of the cover which forms the back is between the grooves. They preferably extend from one edge of the cover to the other. 10 The said grooves may be produced in a suitable way, as for instance by means of a rule or male die brought against the material of which the cover is composed by a considerable blow, and pressing the same into a groove or female die, and this has the effect of pressing the lining and the backing into the grooved shape shown, which in the finished article presents a pronounced grooved appearance. The hinges may, if desired, be 15 formed in the covers at the same time that they are cut out of the sheet, if dies are employed for this purpose, by suitably grooving and beading the respective faces of the said dies. It will be further found that the 20 production of the hinge joints is accomplished without causing the separation of the layers at the groove and that the effect of the formation of the grooves has been to impart a sufficient degree of flexibility to 25 the grooved portion of the cover so that the sides or flaps a, a¹ may be folded to and fro on their respective hinges without straining the same, and that they will readily remain in position as desired. The hinge joint produced according to my invention will, for a 30 book having dimensions about 4 $\frac{1}{2}$ x 2 $\frac{1}{2}$, and a thickness of about $\frac{1}{16}$ of an inch, be ample for the purpose of performing its function, if the same is formed the width of about $\frac{1}{16}$ of an inch. The width may be varied as 35 the size of the book varies, or the thickness of the material of which the cover is formed. I have illustrated in connection with my invention the employment of metal binding parts comprising a spring plate G, made of suitable spring metal and having its lower surface round and its upper edges bent inwardly toward one another forming the usual flanges g, upon the inner edges of 40 which are mounted the prongs or half rings H, H¹, each of which is provided with a slot h in its rear edge adapted to pass over the edge of its supporting flange g and which is 45 frequently seated in a recess formed in the said edge. The lower edges of the mating

prongs H, H¹ are provided with a tongue and groove connection h¹ which permits the parts to play relatively to one another. The tongue and groove connection is outside of the line of the direct thrust of the springs 70 when open, and the tongue and groove in that position prevent the book flying farther apart, and keep the springs under strain. In their closed position the tongue and groove connection is inside of the line of 75 spring pressure and the springs are buckled in opening or closing the prongs.

A back plate I is provided which is well located on the outside of the back of the cover. This is curved in cross section, as 80 seen in Fig. 7, so as to impart a slight curvature to the back of the cover, as illustrated in Fig. 1. Lugs i, illustrated as formed at the ends of the back plate I, illustrated in Figs. 6 and 7 as straight, are bent 85 to extend through the cover and are suitably secured to the spring plate G, as for instance by being bent into notches i¹ therein.

The spring plate, prong construction and supports and back plate do not form part 90 of this invention. However, the temporary binder produced by the use of the said parts with the cover forming a part of this invention produces a novel and desirable structure in that the full strength of the material 95 of which the cover is composed is available at the back portion where the metal parts are supported, and thereby a desirable increase in the strength of the supporting parts is provided. Further by providing 100 the hinge joints I am enabled to avail myself of the thickened cover and consequent increased strength at the points where the hinges are produced and thereby have the advantages of a cover which easily opens or 105 closes and stays in adjusted position without springing. These advantages so far as I am aware could be obtained otherwise only by decreasing the thickness of the cover at 110 the hinge thereby sacrificing strength and durability.

My invention includes the provision of improved means for opening the prongs, and these are illustrated as short stubs J, K. These stubs are perforated at j to pass 115 upon the rings, and they are located between the bunch of leaves L carried by the rings and the covers a, a¹ respectively. The short stubs are composed of small, light, stiff material, for which purpose I have 120 found light fabric board or heavily plated paper stock of tough construction, such as light leather board, to be well adapted, for this possesses sufficient strength so that the perforations will not be torn out during the 125 act of opening the rings, and yet it is so light that its weight does not appreciably add to the weight of the binder, and the expense of production is slight.

The cover A may be improved by the ad-

dition thereto of crease lines M formed therein near the border, but the same do not form part of my invention. The cloth here-tofore employed by me for the purpose of 5 the lining C has been a book binders' cloth which as usually supplied has a size or a suitable adhesive solution thereon, and this is extremely suitable for the purpose as the adhesive assists in preventing the fraying 10 of the edge in use.

I have illustrated the best manner of constructing my invention, but it will be apparent that the invention is not limited to all the particulars noted; for instance, the 15 cover is described as formed of one layer of paper backing having a cloth lining thereto. These materials are not indispensable, nor the number of layers in the backing. Likewise I have illustrated the hinge joint as 20 being employed upon this particular cover, but however I may, within my invention, employ this hinge joint upon a single layer cover, or upon a greater number of layers. These and other modifications of my invention 25 may be made within the limits of the appended claims without departing therefrom. Nor do I limit myself to the use of the particular metal parts illustrated, as other constructions could be employed.

30 In the practical application of my method I have found it preferable to apply the outer lining to the body in a sheet, to then cut the sheet up in cover blanks and as the last step to apply the inner liquid coating, 35 but my invention could be employed within the limits of the following claims by coating the sheet with the liquid coating before it is cut up.

What I claim and desire to secure by Letters Patent is:—

1. A cover for a temporary binder, comprising a fibrous body, an outer lining secured thereto, an inner coating of adhesive, a prong-carrying spring plate inside of said 45 cover, an outer plate, means for securing the parts together comprising lugs on the outer plate adapted to pass through the cover and secured to the spring plate, and hinge joints formed in said cover comprising 50 grooves therein on each side of said back plate and parallel with the edges thereof.

2. A cover for a temporary binder comprising an integral fibrous body of substantially uniform thickness throughout the area thereof, loose-leaf binding mechanism inside of said cover, an outer plate, means for securing the parts together comprising lugs on one of said parts adapted to pass 55 through the cover and secured to the other part, and hinge joints formed in said cover comprising parallel grooves and between which the back is formed.

3. A cover for a temporary binder formed

of a body of paper, a cloth lining affixed thereto and said paper having an inner coating of adhesive and said several materials extending continuously throughout the cover, and said cover having hinge joints formed therein by parallel grooves located at each side of the back portion and extending from edge to edge of the cover, a spring prong-carrying plate in said cover, a back plate on the outside thereof and between 75 said grooves, and means for securing the parts together comprising lugs on the back plate passing through the cover and secured to the prong plate.

4. A temporary binder comprising a spring plate, prongs mounted therein and adapted to be moved to open or closed position and to be maintained in such position by the said plate, and means for simultaneously opening all said prongs comprising short perforated stubs, mounted on each 80 prong, between the leaves of the book and the respective sides of the cover.

5. A temporary binder comprising a cover having a fibrous body, an outer lining secured thereto, and wherein the tendency of 90 the body to warp has been corrected by an inner coating of liquid, a spring plate, prongs therein, a back plate and means for securing said parts together comprising lugs on the back plate passing through the cover 95 and secured to the spring plate, hinge joints in the cover comprising grooves therein on each side of the back plate, and means for opening the prongs comprising short, perforated stubs, mounted on each prong, between the leaves of the book and the respective sides of the cover.

6. A cover comprising a body of fibrous material, an outer lining secured thereto and an inner coating of adhesive material, 105 said lining and coating extending substantially throughout the sides of the cover.

7. A cover comprising a body of fibrous material, an outer lining of textile material affixed thereto, and an inner coating of adhesive material.

8. A cover comprising a backing, an outer lining connected thereto, and an inner coating of adhesive material.

9. A cover comprising a body of fibrous material, an outer lining affixed thereto, and an inner coating of adhesive material, said cover formed of a continuous piece and being of substantially uniform thickness throughout.

10. A cover formed of a body of paper, a cloth lining affixed thereto and said paper having an inner coating of adhesive and said several materials extending continuously throughout the cover.

11. A cover comprising a backing, an outer lining affixed thereto, and an inner coating of adhesive material, said several materials

- extending throughout the dimensions of said cover.
12. A cover for a temporary binder formed of flexible material of substantially uniform thickness throughout, loose leaf binding mechanism within said cover, retaining devices for said binding mechanism passing through said cover and said cover having hinge joints formed therein comprising a pair of substantially parallel grooves formed in the cover on each side of said binding mechanism, the material in said grooved portions being displaced from the plane of the adjacent material in the cover on both the inside and outside of the cover and said grooves having their convex sides extending inwardly of said cover.
13. A flexible cover for a temporary binder formed of a plurality of layers of material each extending throughout the entire area of the cover and directly attached to each other throughout and of substantially uniform thickness throughout, loose leaf binding mechanism within said cover, retaining devices for said binding mechanism comprising members having enlarged portions on the outside of said cover and having portions passing through said cover and secured to said binding mechanism and said cover having hinge joints formed therein comprising a pair of substantially parallel grooves formed in the cover on both sides of the back, the material in said grooved portions being displaced from the plane of the adjacent material in the cover on both the inside and outside of the cover, and said grooves having their convex sides extending inwardly of said cover.
14. A cover formed of a fibrous body, an outer textile lining secured thereto and an inner coating of adhesive, said material extending throughout the cover and having hinge joints formed therein by an inwardly extending crease on each side of the back.
15. A cover formed of a fibrous body, an outside lining affixed thereto and an inner coating of adhesive, the said several layers extending throughout the area of the cover and each of them terminating at the outer edge thereof.
16. A cover formed of a fibrous body, an outside lining affixed thereto and an inner coating of adhesive, the said several layers extending throughout the area of the cover and each of them terminating at the outer edge thereof, and hinge joints formed therein by inwardly extending grooves located at each side of the back portion of the cover and extending from edge to edge of the cover.
17. In a temporary binder a cover comprising a fibrous body, an outer lining affixed thereto and wherein the tendency of the body to warp has been corrected by the application to the inner surface of a coating of liquid, the several parts of the cover extending throughout the area thereof.
18. A cover comprising a fibrous body, an outer lining affixed thereto and wherein the tendency of the body to warp has been corrected by the application to the inner surface of a coating of liquid, the several parts of the cover extending throughout the area thereof.
19. A cover comprising a fibrous body, an outer lining affixed thereto and wherein the tendency of the body to warp has been corrected by the application to the inner surface of a coating of liquid, the several parts of the cover extending throughout the area thereof.
20. The process of forming covers which consists in cementing a lining to the outer surface of a body sheet, in cutting cover blanks out of the sheets so treated, and in applying a liquid coating to the inner surface of the covers.
21. The process of forming covers which consists in cementing a lining to the outer surface of a body sheet, in cutting cover blanks out of the sheets so treated, in providing hinge joints in said material by forming parallel grooves therein, said grooves spaced apart to provide a back between them, and in applying a liquid coating to the inner surface of the covers.
22. The process of forming covers which consists in cementing a lining to the outer surface of a body portion and applying a liquid coating to the inner surface of the covers.
23. A cover for a temporary binder comprising an integral fibrous body of substantially uniform thickness throughout the area thereof, loose leaf binding mechanism inside of said cover, means for securing the said parts together which pass through the back of said cover and hinge joints formed in said cover comprising parallel inwardly extending grooves between which the back is formed, the material in said grooved portions being displaced from the plane of the adjacent material in the cover on both the inside and outside of the cover and said grooves having their convex sides extending inwardly of said cover.
24. A cover for a temporary binder formed of a body of paper, a cloth lining affixed thereto throughout the area of said cover, and said cover being of substantially uniform thickness throughout and having hinge joints formed therein by parallel grooves located at each side of the back portion of the cover.

tion and extending from edge to edge of the cover, the material in said grooved portions being displaced from the plane of the adjacent material in the cover on both the inside and outside of the cover and said grooves having their convex sides extending inwardly of said cover, a prong carrier in said cover, a retaining device on the outside of the cover and between the grooves and means for se-

uring the parts together which pass 15 through the back of the cover.

In witness whereof, I have hereunto signed my name in the presence of two subscribing witnesses.

CLARENCE D. TRUSSELL.

DISCLAIMER.

1,194,684.—*Clarence D. Trussell*, Poughkeepsie, N. Y. TEMPORARY BINDER AND METHOD OF FORMING THE SAME. Patent dated August 15, 1916. Disclaimer filed June 25, 1926, by the assignee, *Trussell Manufacturing Company*.

Hereby enters this disclaimer to the following parts of the specification and claim which are in the following words, to wit:

“A further object of the invention consists in the provision of simple and economical opening means for the prongs.” (Lines 46 to 48, inclusive, page 1.)

“A further object of my invention is in the provision of simple and economical opening means for the prongs.” (Lines 16 to 18, inclusive, page 2.)

“My invention includes the provisions of improved means for opening the prongs, and these are illustrated as short stubs J, K. These stubs are perforated at *j* to pass upon the rings, and they are located between the bunch of leaves L carried by the rings and the covers *a a'* respectively. The short stubs are composed of small, light, stiff material, for which purpose I have found light fabric board or heavily plated paper stock of tough construction, such as light leather board, to be well adapted, for this possesses sufficient strength so that the perforations will not be torn out during the act of opening the rings, and yet it is so light that its weight does not appreciably add to the weight of the binder, and the expense of production is slight.” (Lines 112 to 129, inclusive, page 3.)

“4. A temporary binder comprising a spring plate, prongs mounted therein and adapted to be moved to open or closed position, and to be maintained in such position by the said plate, and means for simultaneously opening all said prongs comprising short perforated stubs, mounted on each prong, between the leaves of the book and the respective sides of the cover.” (Lines 79 to 87, inclusive, page 4.)
